(57) **CLAIM**

The ornamental design for a portion of a keyboard, as shown
and described.

DESCRIPTION

FIG. 1 is a perspective view of a portion of a keyboard
showing my new design;

FIG. 2 is a top view thereof;

FIG. 3 is a rear view thereof;

FIG. 4 is a left side view thereof; and,

FIG. 5 is a right side view thereof.

The contrast in shading techniques represents a contrast in
appearance and does not represent any specific color, mate-
rial or texture. The broken line immediately adjacent to the
shaded area represents an unclaimed boundary of the design.
The broken line showing of the remainder of the keyboard
is for illustrative purposes only and forms no part of the
claimed design.
